CLAIM

(57) The ornamental design for a holder for a device for delivering cellular material and physiologic fluids, as shown and described.

DESCRIPTION

FIG. 1 is a top, right, front isometric view of a holder for use in a device for delivering cellular material and physiologic fluids showing our new design;

FIG. 2 is a bottom, left, rear isometric view;

FIG. 3 is a front elevational view;

FIG. 4 is a right side elevational view;

FIG. 5 is a rear elevational view;

FIG. 6 is a left side elevational view;

FIG. 7 is a top plan view;

FIG. 8 is a bottom plan view;

FIG. 9 is a top, right, front isometric view of the holder in a device for delivering cellular material and physiologic fluids that includes a micrometer and syringe and needle assembly, shown in broken lines;

FIG. 10 is a rear elevational view of the holder in the device; and,

FIG. 11 is a bottom plan view of the holder in the device. The broken lines depict environmental structure only and form no part of the claimed design.
